UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 30, 1923. Serial No. 635,513.

To all whom it may concern:

Be it known that I, RONALD A. McCANN, a citizen of the United States, residing at Swissvale, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus of the type wherein the cars or trains are governed by energy supplied from the trackway. More particularly my invention relates to the trackway portion of such apparatus.

I will describe two forms of apparatus embodying my invention, and will then point out the novel features thereof in claims.

20 In the accompanying drawings, Fig. 1 is a diagrammatic view showing one form of trackway apparatus embodying my invention. Fig. 2 is a view showing a modification of the apparatus shown in Fig. 1 and 25 also embodying my invention.

Referring first to Fig. 1, the reference character A designates the track rails of a railroad over which traffic normally moves in the direction indicated by the arrow. 30 These rails are divided by means of insulated rail joints 1 into a plurality of track sections B—C, C—D, D—E, etc. Each of these track sections is provided with a source of track circuit current, which, as shown in 35 the drawing, comprises the secondary winding 5 of a track transformer designated by the reference character T with an exponent corresponding to the location. The secondary winding is connected across the rails adjacent the exit end of the section. The 40 primary winding 6 of each transformer T is constantly supplied with alternating current from two line wires 7 through wires 32 and 33. These line wires 7 are connected 45 with an alternator 8. Each section is also provided with a track relay designated by the reference character R with a suitable exponent, which relay is connected across the rails adjacent the entrance end of the section. Thus it is clear that each track section 50 is provided with a track circuit which includes a secondary winding 5 of a trans-

former T, a track relay R and the rails of the section in series.

Each section is provided with a signal 55 designated by the reference character S with an exponent corresponding to the location and having an upper semaphore blade 80 and a lower semaphore blade 90. The upper blade 80 of each signal is capable of 60 assuming three positions at 0, 45 and 90 angular degrees with respect to its mast, which positions I shall hereinafter term the "proceed", "caution" and "stop" positions of the blade respectively. The upper blade 65 80 operates three signal circuit controllers L, M and N in the usual and well known manner. The lower blade 90 of each signal is capable of assuming two positions at 0° and 90° with respect to its mast, which positions I will hereinafter term the "proceed" 70 and "stop" positions of the blade respectively. A signal circuit controller P is controlled by the lower blade 90 of each signal 75 in the usual manner.

Each section is provided with two other relays J and K whose control and purpose will be discussed in detail hereinafter. Each section is also provided with a local transformer designated F, and a line transformer 80 G, the primaries of both of which are connected with the line wires 7.

An impedance 2 is connected across the rails adjacent the entrance end of each section, a similar impedance 4 is connected 85 across the rails adjacent the exit end of each section, and a third similar impedance 3 is connected across the rails at an intermediate point in each section.

Referring particularly to section D—E, 90 the lower blade 90 of signal S^D is operated by a mechanism not shown in the drawing, but which when energized moves the signal blade to the proceed position and when de-energized allows the blade to move to the 95 stop position to which it is biased by some force such as gravity. This mechanism is provided with a circuit which passes from the left hand terminal of secondary winding 42 of transformer G^D, through wires 45 and 74, front contact 54—76 of relay J^D, wire 72, signal circuit controller L^D on signal S^D, wire 71, operating mechanism of the lower blade 90 of signal S^D and wires 51, 20 and 100

46, back to the right hand terminal of secondary winding 42 of line transformer G^P . This circuit is closed only when relay J^P is energized and the upper blade 80 of 5 signal S^P is at caution.

The upper blade 80 of signal S^P is also operated by a suitable mechanism not shown in the drawing, which mechanism is provided with a caution circuit and a proceed 10 circuit. The caution circuit passes from the left hand terminal of secondary winding 42 of line transformer G^P , through wires 45, 74 and 73, front contact 68—69 of relay R^P , wire 70, the operating mechanism of the 15 upper blade 80 signal S^P and wires 51, 20 and 46, back to the right hand terminal of secondary winding 42 of transformer G^P . This circuit is closed only when relay R^P is energized. The proceed circuit for this 20 blade passes from the left hand terminal of secondary winding 42 of transformer G^P through wires 45 and 47, front contact 48—49 of relay R^P , wire 50, the operating mechanism of the upper blade 80 of signal 25 S^P and wires 51, 20 and 46 back to the right hand terminal of the secondary winding 42 of transformer G^P . This circuit is closed only when relay K^P is energized. The 30 operation and control of each of the signals 20 S^B , S^C and S^E is exactly the same as for signal S^P .

Still referring particularly to section D—E, the relay K^P is provided with a circuit which passes from the left hand terminal of secondary winding 42 of transformer G^E , wire 44, contact P^E , wire 64, front contact 55—56 of relay J^P , wire 55, winding of relay K^P and wires 52, 20 and 46, back to the right hand terminal of secondary winding 42 of transformer G^E . This circuit is of course closed only when relay J^P is energized and the lower blade 90 of signal S^E is at proceed, thereby closing the contact P^E . A branch is provided 45 for this circuit which passes from wire 44, through contact N^E and back to wire 64. This branch is closed only when the upper blade 80 of signal S^E is at proceed. The relay J^P is provided with a circuit which 50 passes from the left hand terminal of secondary winding 42 of transformer G^E , through wire 44, contact M^E , wire 65, front contact 67—66 of relay R^P , wire 62, winding of relay J^P , and wires 63, 20 and 46, 55 back to the right hand terminal of secondary winding 42 of transformer G^E . This circuit is closed only when relay R^P is energized and the upper blade 80 of signal S^E is at caution or proceed, thus 60 closing contact M^E . Each local transformer F comprises two secondary windings 41 and 40. Referring to transformer F^P , one of these secondary windings 41 is provided with a circuit which passes from 65 its left hand contact, through wire 77,

front contact 58—59 of relay J^P , wire 39, to the mid point of impedance 2 in section C—D, thence down both rails of the section in parallel to impedance 4 in section C—D, wires 27 and 61 back to the 70 right hand terminal of secondary winding 41 of transformer F^P . This circuit is closed only when relay J^P is energized. The secondary winding 40 of transformer F^P is supplied with a circuit which passes from 75 its left hand terminal, through wire 28, front contact 11—12 of relay K^P , wires 27 and 27, to the mid point of impedance 4 in section C—D, thence down both rails in 80 parallel to impedance 2, wire 39, back contact 58—57 of relay J^P and wire 78, to the right hand terminal of secondary winding 40 of transformer F^P . This circuit is closed only when relay R^P is energized and relay J^P is de-energized. This circuit is 85 provided with a branch which passes from wire 28 through back contact 11—13 of relay R^P , wire 29, to impedance 3 in section C—D, and thence back to the rails of the section. The circuit is closed through this 90 branch only when relays R^P and J^P are both de-energized. It is evident that a local current of the one relative polarity which I will call "normal" relative polarity, may be supplied to the rails in parallel 95 throughout the length of the section or a local current of the other relative polarity, which I will call "reverse" relative polarity, may be supplied to the rails in parallel throughout the length of a section or from 100 the entrance end to an intermediate point of the section depending on whether the associated relays are energized or de-energized.

Before explaining the operation of the 105 system as a whole it should be pointed out that the trackway apparatus here shown is intended for co-operation with train carried governing apparatus which operates in the following manner: When the train is on a 110 portion of track which is supplied with local current of normal relative polarity and also with track circuit current, the governing apparatus permits the train to travel at high speed, such as 65 miles per hour. 115 When the train occupies a portion of track which is supplied with local current of reverse relative polarity and also with track circuit current, the governing apparatus prevents the train from proceeding at more than an intermediate speed such as 35 miles per hour; but when the train enters a portion of track from which the supply of either line current or track circuit current is discontinued, the governing apparatus 120 prevents the train from proceeding at more than a low speed of 10 miles per hour. One form of governing apparatus which will co-operate in this manner with the trackway 125 apparatus herein shown, is illustrated and 130

described in United States Letters Patent No. 1351771, issued to Lloyd V. Lewis, Sept. 7, 1920.

The operation of the entire system is as follows:

As shown in Fig. 1 the section to the right of E is occupied by a train V, which de-energizes relay R^E. This in turn de-energizes relays J^E and K^E and allows both blades 80 and 90 of signal S^E to move to stop. The section D—E is supplied with local current of reverse relative polarity between impedances 2 and 3 but is not supplied with local current between impedances 3 and 4. Since section D—E is unoccupied, relay R^D is energized and local current of reverse relative polarity is supplied to the section C—D throughout its length. Relays J^D and K^D are both de-energized and the upper blade 80 of signal S^D is at caution while the lower blade 90 remains at stop. Since contact M^D is closed because the upper blade of signal S^D is at caution, relay J^C is energized. Relay R^C is also energized but relay K^C is de-energized. Thus the section B—C is supplied with local current of normal relative polarity throughout its length and the upper blade 80 of signal S^C remains at caution whereas the lower blade 90 is caused to indicate proceed. Relays R^B, J^B and K^B are all energized, thus moving the upper blade of signal S^B to proceed which allows the lower blade to return to stop. The section to the left of B is supplied with local current of normal relative polarity. All the unoccupied sections are provided with track circuit current so a train following V and travelling in the direction of the arrow over that portion of track shown in Fig. 1 could proceed at high speed as far as point C, where its speed would be reduced to 35 miles per hour. It could proceed at this speed as far as impedance 3 in section D—E but beyond this point it could not proceed at speeds in excess of 10 miles per hour because of the interruption of local current, while beyond point E the low speed limitation is still effective because the wheels and axles of train V shunt all the track circuit current away from the governing apparatus.

In Fig. 2 I have modified the arrangement of trackway apparatus shown in Fig. 1 to suit conditions where roadside signals are not in use. In this view each section is provided as before, with impedances 2, 3 and 4, track transformer T, line transformer G and track relay R. Each section is also provided with a line relay H. In this case the local transformer F for each section is only provided with one secondary winding 10. Its primary 9 is energized as before from line wires 7. Referring particularly to transformer F^D the secondary 10 of this transformer is provided with a circuit which

passes from its left hand terminal through wires 35 back contact 22—23 of relay H^D, wire 39, impedance 2, of section C—D, the rails of the section in parallel to impedance 4, thence through wire 27, front contact 11—70 12 of relay R^D, wires 28 and 38, back contact 25—26 of relay H^D, and wire 37, back to the right hand terminal of secondary winding 10 of transformer F^D. This circuit is closed only when relay R^D is energized and relay H^D is de-energized. A branch is provided for this circuit which branch passes from the rails of the section C—D through impedance 3, wire 29, back contact 11—13 of relay R^D, and back to wire 28. The circuit is closed through this branch only when relays R^D and H^D are both de-energized. This secondary winding 10 is provided with another circuit which passes from its left hand terminal through wire 35, front contact 22—21 of relay H^D, wire 28, front contact 11—12 of relay R^D, wire 27, impedance 4 of section C—D down both rails of the section in parallel to impedance 2, thence by wire 39, front contact 25—24 00 of relay H^D and wire 37 back to the right hand terminal of secondary winding 10 of transformer F^D. This circuit is closed only when relays R^D and H^D are both energized. The relay H^D is provided with a circuit 95 which passes from the left hand terminal of secondary winding 42 of transformer G^E through wire 31, front contact 15—14 of relay R^E, wire 30, front contact 17—16 of relay R^D, wire 18, winding of relay H^D, 100 and wires 20 and 19 back to the right hand terminal of secondary winding 42 on transformer G^E. This circuit is closed only when relays R^D and R^E are both energized. 105 As shown in the drawing a train V occupies the section to the right of E. As a result relays R^E, H^D and H^E are de-energized. Thus local current of reverse relative polarity is supplied to the rails of section D—E between impedances 2 and 3 while no local current is supplied to the rails of section D—E between impedances 3 and 4. Relay R^D is energized and local current of reverse relative polarity is supplied to the rails of section C—D throughout its length. 110 Relays R^C and H^C are both energized, thus supplying local current of normal relative polarity to the rails of the section B—C. Likewise, relays R^B and H^B being energized, the rails of the section to the left of B are supplied with local current of normal relative polarity. The operation of the governing apparatus over the portion of track shown in Fig. 2 is exactly like that described in Fig. 1. 115

Although I have herein shown and described only two forms and arrangements of railway traffic controlling apparatus embodying my invention, it is understood that various changes and modifications may be 120 125 130

made therein within the scope of the appended claims without departing from the spirit and scope of my invention.

Having thus described my invention, 5 what I claim is:

1. In combination, a plurality of successive sections of railway track, a track circuit for each section comprising the rails of the section in series, a source of alternating current for said track circuit, and means for supplying local current of one relative polarity to the rails of each section in parallel between the entrance end and an intermediate point in the section 10 when the section in advance is occupied and between the entrance and the exit ends of the section when the section in advance is unoccupied and the second section in advance is occupied, and for supplying local current of the other relative polarity to the rails of the section in parallel between the entrance end and the exit end when the section in advance and the second section in advance are unoccupied.
2. In combination, a plurality of successive sections of railway track, a track circuit for each section comprising the rails of the section in series, a source of alternating current for said track circuit, a track 15 relay for each section, a signal for each section, means controlled in part by said signal and said relay for supplying the rails in parallel of the section next in the rear with local current of one relative polarity from the entrance end to an intermediate point in the section, or of one or the other relative polarity between the entrance and exit ends of the section.
3. In combination, a plurality of successive sections of railway track, a track circuit for each section comprising the rails of the section in series, a source of alternating current for said track circuit, a track relay for each section, a second relay for each section controlled in part by said track relay, a third relay for each section controlled in part by said second relay, a signal for each section controlled by said track relay and said second and third relays, and means controlled by said track relay and said second relay for supplying the rails in parallel of the section next in the rear with local current of one relative polarity from the entrance end to an intermediate point in the section or of one or the other relative polarity between the entrance and exit ends of the section.
4. In combination, a plurality of successive sections of railway track, a track circuit for each section comprising the rails of the section in series, a source of alternating current for said track circuit, a track relay for each section, a second relay for each section controlled by the associated track relay and the track relay next in advance, a third relay

for each section controlled by the associated second relay and the track relay of the section next in advance, a signal for each section controlled by its associated track relay and second and third relays, and means controlled by said track relay and said second relay for supplying the rails in parallel of the section next in the rear with local current of one relative polarity from the entrance end to an intermediate point in the section or of one or the other relative polarity between the entrance and exit ends of the section.

5. In combination, a plurality of successive sections of railway track, a track circuit for each section, a source of current for each said circuit, a track relay for each section, a signal having two semaphore blades for each section; a first, a second and a third signal circuit controller operated by the upper blade of each said signal; a fourth signal circuit controller operated by the lower blade of each said signal; a second relay for each section, a third relay for each section, a local transformer for each section; a circuit for said second relay including a source of energy, a front contact on its associated track transformer and the said first signal circuit controller of the section next in advance; a circuit for said third relay including a source of energy, a front contact of its associated second relay, and the second or the third signal circuit controller of the section next in advance, a secondary winding on said local transformer, a circuit for said secondary including a front contact on said second relay and the rails in parallel of the section next in the rear, a second secondary winding on said local transformer; a circuit for said second secondary including the rails, in parallel, of the section next in rear, a back contact on said second relay, and a front contact on said track relay, and a second circuit for said secondary including the rails in parallel of the section next in rear between the entrance end and an intermediate point in the section, a back contact on said track relay and a back contact on said third relay.

6. In combination, a plurality of successive sections of railway track, a track circuit for each section comprising the rails of the section in series, a source of alternating current for said track circuit, a track relay for each section, a line relay for each circuit, and means controlled by said track relay and said line relay for supplying local current to the rails in parallel of the section next in the rear with local current of one relative polarity from the entrance end to an intermediate point in the section or of one or the other relative polarity between the entrance and exit ends of the section.

7. In combination a plurality of successive sections of railway track, a track

circuit for each section comprising the rails of the section in series, a source of alternating current for said track circuit, a track relay for each section, a line relay for each section; a circuit for each said line relay comprising a source of energy, a front contact on its associated track relay and the track relay for the section next in advance, a local transformer provided with a secondary winding; a circuit for said winding including the rails in parallel of the section next in rear, a front contact on said track relay, a front contact on said line relay and a second front contact on said line relay; a

second circuit for said secondary comprising the rails in parallel of the section next in rear, a front contact on said track relay, a back contact on said line relay and a second back contact on said line relay; a third circuit for said secondary comprising the rails in parallel of the section next in rear between the entrance end and an intermediate point in the section, a back contact on said track relay, a back contact on said line relay and a second back contact on said line relay. 15 20 25

In testimony whereof I affix my signature.

RONALD A. McCANN.
